CLAIM

The ornamental design for a disposable container, as shown and described.

DESCRIPTION

FIG. 1 is a perspective view of a first embodiment of a disposable container, embodying my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right end elevational view thereof;

FIG. 7 is a left end elevational view thereof;

FIG. 8 is a perspective view of a second embodiment of a disposable container embodying my new design;

FIG. 9 is a top plan view thereof;

FIG. 10 is a front elevational view thereof;

FIG. 11 is a rear elevational view thereof;

FIG. 12 is a bottom plan view thereof;

FIG. 13 is a right end elevational view thereof; and,

FIG. 14 is a left end elevational view thereof.
